UNITED STATES PATENT OFFICE.

MENDEL PIANKO, OF BROOKLYN, NEW YORK.

WINDOW-STAND.

SPECIFICATION forming part of Letters Patent No. 424,351, dated March 25, 1890.

Application filed July 26, 1889. Serial No. 318,764. (No model.)

To all whom it may concern:

Be it known that I, MENDEL PIANKO, of Brooklyn, in the county of Kings and State of New York, a citizen of the United States, 5 have invented certain new and useful Improvements in Window-Stands, of which the following is a specification.

This invention relates to certain improvements on the window-stands for which Letters Patent were granted to Kazimieras Bukawietis, No. 399,491, dated March 12, 1889, said improvements being designed with a view to increase the safety of the window-stand in cleaning the window, and permitting the convenient folding up of the stand when not in use.

The invention consists of a window-stand which is formed of bars that are supported on the sill and connected by a transverse retaining-bar, and keys passing through the main bars, the outer ends of the main bars being united by transverse seat-forming slats which are held by pins of the main bars and provided with a folding railing formed of a top bar and folding straps pivoted to the transverse slats and the top bar and to each other, so as to permit their being folded up and detached from the main supporting-bars. The main bars are supported by inclined braces, 25 which are provided with a detachable step at the lower part and with rests at the lower ends of said braces. A foot-board is connected with the seat-slats by an apron which is connected with the front seat-slat and the rear edge of the foot-board, and which serves 30 to hide the feet of the person cleaning the window.

In the accompanying drawings, Figure 1 represents the vertical transverse section of my improved window-stand on line 2 2, Fig. 2. Fig. 2 is a top view of the same; and Fig. 3 is a side view of the railing, foot-board, and apron connecting the seat-slats with the foot-board, all the parts being shown detached 45 from the supporting-frame of the stand and folded up.

Similar letters of reference indicate corresponding parts.

Referring to the drawings, A represents the 50 main supporting-bars, which are supported on

the sill and extended to the outside of the window, parallel to each other. The inner ends of the main bars A are connected by a transverse retaining-bar A', which is held in position against the wall of the building by 55 means of pins or keys a, which are passed through openings a' in the inner ends of the bars A, as shown clearly in Figs. 1 and 2. The outer ends of the supporting main bars A are provided with fixed pins b, to which are 60 applied transverse slats B to form a seat for the person cleaning the window. To the outer ends of the main bars A are applied, by a suitable hinge-connection, inclined braces D, which are connected by means of links D' 65 with the bars A, which links pass through eyes d of the braces and engage at their upper ends notches d' in the upper edges of the main bars A. The lower ends of the hinged braces D are provided with pins e, which pass 70 through holes of a transverse foot-board E, so as to hold the same in position. The lower ends of the inclined braces D are provided with rests D², which abut against the wall of 75 the building and prevent the injuring or scratching of the same.

To the ends of the seat-slats B, as well as to the outer edge of the outermost slat B, are applied pivoted and folding straps f, each of which is made of two sections which are pivoted together, the upper ends being again pivoted to a U-shaped frame F, so as to form a railing when the two sections of the strips are placed in line with each other. The railing F may be folded down upon the slats by 85 means of pivoted straps f, and removed with the seat-slats from the supporting-frame, as shown in Fig. 3, when the window-stand is not required for use. The seat-slats are connected with each other by straps or braces M. 90 The front slat B is connected with the rear edge of the foot-board E by an apron G, which is made of leather, canvas, or other suitable material, and which serves for the purpose of concealing the feet and legs of the person on 95 the seat, so as to prevent them from being seen from the street. The railing and apron impart a greater feeling of security to the person sitting on the window-stand, by providing supports for the arms.

As the railing, seat-slats, and foot-board can be detached from the supporting-bars, they can be conveniently stored away for further use.

5 Having thus described my invention, I claim as new and desire to secure by Letters Patent—

1. In a window-stand, the combination of supporting main bars applied to the sill by a 10 transverse retaining-bar, keys or pins passing through said main bars, inclined braces hinged to said supporting-bars and having rest-blocks at their lower ends and links for connecting the braces with the main bars, detachable 15 seat-slats supported on pins of the main bars, a railing formed of a top frame, and folding slats pivoted to the top frame and to the seat-slats, substantially as set forth.

2. In a window-stand, the combination, with 20 main bars to be supported on a window-sill, of a transverse retaining-bar through which said main bars are passed, keys for locking the main bars to the retaining-bar, inclined braces hinged to the outer ends of the main 25 bars and provided with rest-blocks at the lower end, links connecting the hinged braces with the main bars, seat-slats supported on pins of the main bars, a detachable foot-board applied to pins of the lower parts of the braces, 30 and an apron connecting the front slat with

the rear edge of the foot-board, substantially as set forth.

3. In a window-stand, the combination of main bars to be supported on a window-sill, a transverse retaining-bar through which the 35 main bars are passed, keys for locking the main bars to said retaining-bar, inclined braces hinged to the outer ends of the main bars and provided with rest-blocks at their lower ends, detachable seat-slats applied to 40 pins of the main bars, a folding railing attached to said seat-slats, a foot-board attached to pins at the lower part of the braces, and an apron connecting the front with the rear edge of the foot-board, substantially as set forth. 45

4. In a window-stand, the combination of detachable seat-slats, a folding railing formed of folding slats pivoted to said seat-slats, of a top frame to which the slats are pivoted, a detachable foot-board, and an apron connecting the front slat with the foot-board, substantially as set forth. 50

In testimony that I claim the foregoing as my invention I have signed my name in presence of two subscribing witnesses.

MENDEL PIANKO.
